UNITED STATES PATENT OFFICE

ERNEST DAVIS, OF SYRACUSE, NEW YORK, ASSIGNOR TO THE PROSPERITY COMPANY INC., OF SYRACUSE, NEW YORK, A CORPORATION OF NEW YORK

FABRICATED BUCK

Application filed July 14, 1930. Serial No. 467,671.

This invention relates to pressing machines and particularly to the construction of a pressing element of such machines.

In the design of garment and laundry presses, it has been conventional practice to employ heavy and expensive castings, from which to construct the pressing elements. When the pressing element was formed of sheet metal parts secured together by such heat processes as welding, it was found impossible to prevent warping of the pressing elements in a great percentage of cases. Other methods of securing sheet metal sections together, such as bolts or rivets, have proved excessively expensive or unsatisfactory due to leaking of the steam from the inside of the pressing element through the joints along which the sheet metal parts were secured together. Another disadvantage which has been met with in the construction of pressing elements from sheet metal sections is in aligning the holes in the various sections through which fastening members must be inserted, or through which steam must be blown in operating the press.

An object of this invention is to provide an improved pressing element which is composed of sheet metal parts and connected together in such a way as to produce a steam tight pressing element which will be economical to build.

A further object of the invention is to provide a pressing element composed of sheet metal parts in which the steam used as a heating medium will be contained in a bag or liner contained within the pressing element.

Other objects and advantages of the invention will appear and will be pointed out as the description proceeds.

The invention consists in the novel features and in the combinations and constructions hereinafter set forth and claimed.

In describing this invention, reference is had to the accompanying drawings in which like characters designate corresponding parts in all the views.

Figure 1 is a diagrammatic side elevation of a pressing machine of the type to which my improved pressing element is particularly adaptable.

Figure 2 is a fragmentary perspective view, partly in section, showing my improved sheet metal pressing element.

Figure 3 is a view showing the face of the pressing element shown in Figure 2.

Figure 4 is a fragmentary perspective view, partly in section, showing the manner of assembling the sheet metal parts of the pressing element shown in Figure 2.

My improved pressing element is designed primarily for use with pressing machines of the head and buck type in which a pressing head or movable buck 10 is movable toward and from a fixed buck 11 which may be supported on a neck 12 which rises from a frame 13 of the pressing machine. The pressing head or movable buck 10 is carried by a suitable yoke 14 which is pivoted at 15 to a standard 16 which rises from the pressing machine frame. The yoke 14 is operated by a motor 17 through a bell crank 18 and connecting link 19. All of this construction is of the conventional type well understood by those skilled in the art.

The pressing head 10 includes a pressing face 21, which may be formed of sheet metal, and a body portion 22 also formed of sheet metal. The body portion 22 is formed with a depressed channel 23 extending along the center line and terminating short of the ends of the body portion. The edges of the body portion are bent downwardly and provided with flanges 25 which contact with the back of the face plate 21. The face plate 21 is secured to the body portion 22 by turning the marginal edges 26 around the flanges 25, as shown in section in Figure 2. Since the joint formed by turning over the marginal edges 26 around the flanges 25 is not likely to be fluid tight a bag 30, preferably constructed of soft metal, is enclosed between the body portion 22 and face plate 21.

The bag 30 forms a lining for the heating chamber of the pressing head 10. This bag 30 is fluid tight and may be constructed from soft sheet metal, such as copper, by securing a top plate 31 which is formed to fit the body portion 22, to a lower plate 32 which is formed to fit the contour of the face plate 21. These plates 31 and 32 may be secured together along

their edges by any suitable means such as by sweating. If the bag 30 is constructed of soft sheet metal it is immaterial whether the metal becomes warped during the process by which the plates 31 and 32 are secured together. Any warping which results at this time will be unimportant because of the fact that the bag is of soft material which will readily adapt itself to the shape of the pressing element in which it is enclosed.

The chamber formed between the body portion 22 and face plate 21 in which the bag 30 is enclosed provides a heating chamber for the pressing element. Heating fluid such as steam is supplied to the bag 30 through suitable means such as a steam pipe 33, which is connected with a source of steam not shown.

A cover plate 35 fits over the top of the depressed channel portion 23 to form a steaming chamber in said depressed channel portion. Suitable means, such as a gasket 36, may be provided between the cover plate 35 and the body portion 22 to prevent the escape of steam between the cover plate and body portion.

Orifices 40 are provided through the face plate 21, bag 30 and body portion 22. Some of these orifices are used for blowing steam from the steaming chamber through the face plate of the pressing element for steaming garments. Other of the orifices are used for inserting fastening means through the sheet metal parts to secure the same together along the center line of the pressing element to obtain greater strength and rigidity.

The steam may be supplied to the steaming chamber by means of a steaming valve 42 which connects with a pipe 43 leading from the interior of the bag 30 in the heating chamber.

The body portion 22 carries a conventional supporting bracket 45 by which it is mounted on the yoke 14 of the pressing machine.

45 *Method of assembling*

The sheet metal pressing element above described is made practical largely through the novel method by which it is assembled. This method is best understood by reference to Figure 4 of the drawings. The face plate 21 is provided with bent up marginal edges 26. The inner bag 30 or liner is made up of a bottom plate 32 of the same general contour as the back of the face plate 21, and a top plate 31 formed with the same general contour as the lower side of the body portion 22. The plates 31 and 32 are secured together along their edges by suitable means such as sweating. These plates 31 and 32 may be also secured together in a similar manner along the center line of the plates where the depressed channel portion of the top plate contacts with the bottom plate 32.

The body portion 22 is formed with flanges 25 along the marginal edges thereof. No

holes or orifices are provided in any of the sheet metal parts before they are assembled. This is due to the fact that in constructing a pressing element of sheet metal parts some shifting of the parts on one another during the assembling process is almost certain to occur with the result that the orifices are thrown out of line and no longer properly register with one another.

The sheet metal parts shown in Figure 4 are brought together and the bent up edges 26 of the face plate 21 are turned over the flanges 25 of the body portion 22 thus securing the face plate to the body portion and clamping the edges of the bag 30, in position. When the parts are thus secured together the holes 40 are drilled through the body portion 22, bag 30, and face plate 21. Some of these holes are left open to permit the passage of steam from the steam chamber through the face plate when steaming garments. Other of the holes are used to receive fastening means for securing the sheet metal parts together along their center line as previously described.

From the above description it will be apparent that I have provided a pressing element composed entirely of sheet metal parts, designed so as to be strong and rigid, and economical to assemble due to the novel method by which the pressing element is made up from the component parts.

The invention is illustrated in its preferred embodiment but various changes and modifications may be made without departing from the spirit of the invention as set forth in the appended claims.

What I claim is:

1. A pressing element including a face plate member and a body member spaced apart from the face plate member throughout a portion of its area and secured to the face plate member by turning the marginal edges of one of said members around the marginal edges of the other of said members; a fluid tight bag within the chamber between the face plate member and the body member; and means for admitting fluid into said bag.

2. A pressing element including a body portion formed with a recess in the bottom side thereof; a fluid tight bag located in said recess; means for admitting fluid to said bag; and a face plate mounted on the body portion to close the recess and form a chamber, and to hold the fluid tight bag within said chamber, the face plate being secured in such position on the body portion by turning the marginal edges of the face plate around the marginal edges of the body portion.

3. As an article of manufacture a pressing element having a face plate member and a body member spaced apart from the face plate member throughout a portion of its area and secured to the face plate member by turning the marginal edges of one of said mem-

bers around the marginal edges of the other of said member, and a lining within the chamber formed by said members to prevent the flow of fluid from said chamber through the 5 seam formed by the marginal edges of said members.

4. As an article of manufacture a pressing element including a body portion formed with a chamber therein and having a face 10 plate closing the bottom of said chamber and secured to the body portion by turning the marginal edges of the face plate around the marginal edges of the body portion, and a lining within the chamber for preventing the 15 flow of heating fluid from said chamber through the seam formed at the marginal edges of said body portion.

5. In a pressing machine a pressing element including a body portion formed with a 20 heating chamber and a steaming chamber therein; a face plate closing the open end of the heating chamber and secured to the body portion by turning the marginal edges of the face plate over the marginal edges of the 25 body portion; a fluid tight container substantially filling the heating chamber; a cover plate closing the open end of the steaming chamber; and means for admitting fluid to the steaming chamber and to the fluid tight 30 container.

6. In a pressing machine a pressing element including a body portion formed with a heating chamber and a steaming chamber therein; a face plate closing the open end of the 35 heating chamber and secured to the body portion by turning the marginal edges of the face plate over the marginal edges of the body portion; a container within the heating chamber for holding the heating fluid to prevent the escape of the heating fluid through the seam formed at the marginal edges of the face plate and body portion; a cover plate closing the open end of the steaming chamber; means for securing said cover plate in 40 position; and means to prevent the escape of steam from the joint between the body portion and cover plate.

7. In a pressing machine a pressing element including a body portion formed with a 50 heating chamber and a steaming chamber therein; a face plate closing the open end of the heating chamber and secured to the body portion by turning the marginal edges of the face plate over the marginal edges of the body portion; a container within the heating chamber for holding the heating fluid; a cover plate closing the open end of the steaming chamber; means for securing said cover plate in position; means to prevent the escape 55 of steam from the joint between the body portion and cover plate; means for admitting steam to the container within the heating chamber; and means for admitting steam from the container in the heating chamber to the steaming chamber.

8. In a pressing machine a pressing element including a body portion formed with a recess in the lower and in the upper side thereof; a face plate closing the open end of the recess in the lower side to form a heating chamber, said face plate being secured to the body portion by turning the marginal edges of the face plate over the marginal edges of the body portion; a fluid tight lining in the heating chamber to prevent the escape of fluid therefrom; a cover plate closing the open end of the recess in the upper side to form a steaming chamber; and means for admitting fluid to the respective chambers. 70

9. A pressing element including a face plate; a body portion secured to the face plate at the marginal edges thereof and spaced apart from the face plate throughout a portion of its area to form a heating chamber; a liner in the heating chamber to render the same leak proof; a depressed channel portion on the body portion forming a recess surrounded by the heating chamber; a corresponding depressed channel portion on the liner for the heating chamber; and means passing through the liner to secure the depressed channel portion of the body portion to the face plate. 80

10. A pressing element including a face 95 plate; a body portion secured to the face plate at the marginal edges thereof and spaced apart from the face plate throughout a portion of its area to form a heating chamber; a liner in the heating chamber to render the same leak proof; a depressed channel portion on the body portion forming a recess surrounded by the heating chamber; a corresponding depressed channel portion on the liner for the heating chamber; means passing through the liner to secure the depressed channel portion of the body portion to the face plate; a cover plate over the recess to form a steaming chamber; means for admitting fluid to the heating chamber; and means for admitting fluid from the heating chamber to the steaming chamber. 100

11. A pressing element including a face plate; a body portion secured to the face plate at the marginal edges thereof and spaced apart from the face plate throughout a portion of its area to form a heating chamber; a liner in the heating chamber to render the same leak proof; a depressed channel portion on the body portion and a cover over said channel to form a steaming chamber surrounded by the heating chamber; a corresponding depressed channel portion on the liner for the heating chamber; and means passing through the liner to secure the depressed channel portion of the body portion to the face plate; orifices being provided through the body portion, lining, and face plate, for permitting steam to flow 115 120 125 130

from the steam chamber through the face plate.

In testimony whereof, I have hereunto signed my name, at Syracuse, in the county of Onondaga, and State of New York, this 5 10th day of July, 1930.

ERNEST DAVIS.
